COUNTING MECHANISM

Edward Wild, Hartford, Conn., assignor to Veed-
er-Root Incorporated, Hartford, Conn., a cor-
poration of Connecticut

Application September 2, 1937, Serial No. 162,159

5 Claims. (Cl. 235—144)

This invention relates to registering mechanism for separately counting the numbers of items of various sorts. My improved counting mechanism has general application where it is desired to separately add and register the numbers of different kinds or sorts of items, pieces, etc., but as instances of uses to which the present invention may be applied, reference may be had to the making up of payrolls in which instance it is necessary for the clerk to determine and obtain from the bank the necessary numbers of pieces of money of different denominations; and the taking of inventories where it is desired to determine how many of each of various articles or pieces of merchandise, etc., are in stock.

The aim of the invention is to provide a counting mechanism of this sort having various features of novelty and advantage and which is characterized by its simplicity, inexpensiveness, compactness, and its flexibility and effectiveness in operation.

More particularly, aims of the invention are to provide an improved counting mechanism having a plurality of separable counter units which may be connected together in aligned relation in any desired number; to provide a counting mechanism having a plurality of counter units in side by side relation and means operable to simultaneously reset all of the units to initial starting position; to provide a counting mechanism of this sort with a totalizer unit wherein may be added all of the items registered within the individual counter units, and to provide a counting mechanism wherein the units may be very easily assembled.

Other objects will be in part obvious and in part pointed out more in detail hereinafter.

The invention accordingly consists in the features of construction, combination of elements, and arrangement of parts which will be exemplified in the construction hereinafter set forth and the scope of the application of which will be indicated in the appended claims.

In the accompanying drawings, wherein like parts are indicated by like numerals:

Figure 1 shows a plan view of a plurality of counter units assembled in aligned relation;

Fig. 2 is a longitudinal section through the assembly of the same and taken along the line 2—2 of Fig. 1;

Fig. 3 is a cross section of an individual counter unit, the same being taken through line 3—3 of Fig. 1;

Fig. 4 shows a cross section through the totalizer unit taken along the line 4—4 of Fig. 1;

Fig. 5 is a section through the assembly, the same being taken along line 5—5 of Fig. 2;

Fig. 6 is an end view showing a plurality of assembled mechanisms arranged in banked relation;

Fig. 7 is a sectional view through line 7—7 of Fig. 2 and shows one of the locking clips which holds the counter wheels against movement longitudinally of the reset shaft carrying the same; and

Fig. 8 is a detail view of certain of the parts.

In accordance with the present invention, I provide an assembly which includes a plurality of individual or sub-counter units C arranged in aligned side by side relation. The number of such units in any given assembly will depend upon the use to which the mechanism is to be applied and, in use, each of the units may be assigned to a particular kind or sort of item, piece, denomination, etc., to be counted. For example, in determining the numbers of different kinds of bills and pieces of silver necessary to make up a payroll, the first unit may be used for adding up the number of five dollar bills necessary, the next unit one dollar bills, the next unit fifty-cent pieces, and so on. The assembly may also include a totalizing unit T arranged in aligned relation with the individual or sub-units and preferably at one end of the line of such units. The counter units are positioned between a pair of end brackets or plates 16 and 17 which are secured together by tie rods 20 having their opposite ends received in opposed recesses of the brackets and secured in place by screws 21. If desired, a plurality of assembled mechanisms may be arranged in banked relation as shown in Fig. 6. In this instance, three banks are illustrated, the same being secured to supports 10 which have feet 11. These supports are suitably stepped as illustrated for locating the banks or counters in conveniently operable positions. The several banks are secured to the supports in any suitable manner, as by screws 18.

The individual counter units C and the totalizer unit T, which are mounted in side by side relation with the totalizer unit at one end, are of generally similar construction with the exception that the totalizer unit does not have an operating key. Hence, these units will be described together with similar parts correspondingly numbered. Each unit has a frame or casing 22 provided with a base 22' having spaced bores 20' for receiving tie rods 20. The frames are each provided with spaced end walls 23 and 24 and an

intermediate partition 25. Each of the units has a correspondingly located reset shaft 26 rotatably mounted at its ends in the walls 23 and 24, and each shaft supports a plurality of rotatable 5 numeral wheels 27 having spaced consecutive numerals thereon running from 0 to 9. Each of the units has a protective cover 16 secured to its casing as by screws, and each cover has a window V through which the counter registration may be 10 observed.

The numeral wheels of succeeding orders in each unit may be interconnected by any suitable transfer mechanism such, for example, as that disclosed in the patent to Slye No. 2,004,881 issued June 11, 1935. It is not necessary to illustrate this transfer mechanism since it does not comprise a novel part of the present invention. A flanged spacer sleeve 28 on the right-hand end of each shaft 26 (Figs. 2 and 8) is non- 20 rotatably secured in position as by a pin 28' extending from wall 24 and slidably received within a slotted portion in the flange 28'. For the purpose of preventing accidental withdrawal of the reset shaft from the casing and retaining 25 the counter wheels and the spacer sleeve 28 in proper relation to one another and against longitudinal movement relative to the reset shaft, clips 30 are provided. These clips are respectively located at the right-hand end of the sleeve 30 28 and at the left-hand end of the counter wheel of highest order. The clips, as shown most clearly in Fig. 7, are flat, thin strips of metal suitably bifurcated to provide arms 30'. The reset shaft has annular grooves 30" in which 35 these arms engage. These clips are so located with respect to the casing walls adjacent thereto that a slight end play of each reset shaft is permitted for purposes to be later described.

When the several counter units are properly 40 assembled in side by side relation, the several reset shafts are in alignment with one another and each shaft is connected with the next preceding one by a driving connection so that the several shafts form a composite sectional reset 45 shaft common to all of the units. In the present illustrative disclosure, the driving connection between the adjacent reset shafts is in the form of a tongue and groove. In the present instance, the left-hand ends of the reset shafts, as viewed 50 in Fig. 2, project outwardly through the end casing walls 23 and have tapered V-shaped tongues 31 provided with flat surfaces. The right-hand end of each of the reset shafts, with the exception of the shaft of the extreme right- 55 hand unit (be that unit an individual counter or a totalizer), is provided with a correspondingly V-shaped groove 31' adapted to matingly receive the tongue of the next preceding shaft. The grooves 31' are tapered correspondingly to 60 the tongue portions 31 which they receive so that a tight interfitting driving relation may exist without lost motion between adjacent reset shafts. The grooved end of each shaft may be journaled in a bearing sleeve 31" supported in 65 a bore of the wall 24. In the present illustrative disclosure, the totalizer unit is shown as being located at the right-hand end of the assembly. In such instance, the driving connection between the left-hand end of the shaft 26 of that unit 70 and the reset shaft of the last individual counter unit also takes the form of a tongue and groove. The right-hand end of the reset shaft 26 of the totalizer unit T projects beyond the end wall 24 of that unit, and bearing against this end 75 wall of that shaft is a spring pressed plunger 32

whereby the reset shafts are urged towards the left as viewed in Fig. 2. The plunger is located in the bore of a bearing portion 33 of the end bracket or plate 17. It has a flanged or enlarged head 34 engaging in a counterbore 33' of the bearing. This head is engageable with a shoulder 34' to limit the movement of the plunger towards the right, as viewed in Fig. 2. A coiled spring 35 surrounds the stem of the plunger and is compressibly engaged between the head 34 of the plunger and a shoulder 35' adjacent the closed end of the bore. In some instances, it may be desirable to omit the totalizer unit, in which case the right-hand end of the reset shaft of the last individual counter unit projects beyond the wall 24 of that unit and engages the spring pressed plunger 32 in the same manner as does the reset shaft of the totalizer unit, as shown in the drawings.

Each reset shaft has a longitudinally extending groove 26' engageable with pawls on the respective numeral wheels mounted thereon, as disclosed in the previously mentioned patent to Slye No. 2,004,881, so that a single complete rotation of the composite reset shaft in a resetting direction will cause a resetting operation to be performed on all of the numeral wheels and return them to initial starting or zero positions. For the purpose of turning the reset shaft to perform the resetting operation, there is journaled in one of the end brackets (in the present instance in the left-hand bracket 16) a reset operating shaft 36 having a knob 37. The reset operating shaft is journaled for endwise movement in the bearing portion 16' of the bracket 35 16. The inner end of the shaft 36 terminates in a head 36' journaled in a counterbore 37' and engageable with a shoulder portion of the bearing to limit the movement of the shaft away from the counter units. A coiled spring 38 surrounding this shaft 36 is compressed between the head 36' and the shoulder 38'. The head 36' has a V-shaped groove 39 corresponding in shape to the grooves 31' and matingly receives the projecting tongue 31 of the reset shaft of 45 the first counter unit.

It will be observed that with the arrangement described, any suitable desired number of counter units may be assembled and secured together. The units are assembled with their reset shafts 50 aligned, the tongue 31 of each reset shaft being engaged in the grooves in the adjacent end of the preceding reset shaft. The units are located between the end brackets 16 and 17, and these brackets are secured together by the rods 20 and 55 the screws 21. The units are supported on these rods and are clamped between the end brackets 16 and 17 so that a rigid assembly is had. If desired, thin spacer washers 75 may be positioned about the rods between the casings and 60 between the end casings and the brackets. It will further be observed that the springs 35 and 38 cooperatively urge the reset shafts into driving relationship, and the reset operating shaft 36 into driving relationship with the reset shaft 65 of the first unit. This results in a tight interfitting driving relationship between all of the reset shafts and the operating shaft 36 irrespective of the number of counter units employed, and a rotation of the reset knob 37 will serve 70 to simultaneously cause a corresponding rotation of all of the reset shafts of the unit without any lost motion between said shafts.

As previously stated, the clips 30 are so located on the reset shafts that these shafts may 75

have a slight longitudinal floating movement. This end play of the reset shafts permits sufficient shaft movement so that the tongues and grooves may enter into tight interfitting driving relation, and this relation is maintained at all times owing to the opposed influence of the springs 35 and 38. These springs urge the reset shafts longitudinally towards each other so that the tongues are maintained snugly and closely within the cooperating grooves so that during the resetting operation the shafts operate as if they were one integral shaft. Thus, lost motion, which may otherwise exist between the shafts, is prevented. It may be stated that if there were any lost motion between the successive reset shafts, it is possible that the counter wheels of the several units would not properly be reset to zero when the operating knob is turned through one complete rotation and this would result in inaccurate subsequent registrations. If any lost motion existed between the reset shafts, it would be accumulative so that the wheels of the last unit would not be reset to the same extent as those of the first unit. With my improved arrangement, these difficulties are entirely avoided in a very simple and effective manner. It is, of course, clear that, if desired, the totalizer unit, where such unit is employed, may be reset independently of the individual counter units.

30 Each of the individual counter units is individually operated by a key lever 40 extending through a slot in the cover 76 and pivotally supported between its ends on a pin 41 mounted in the wall 24 and the partition 25. The outer ends of these levers may be provided with buttons or keys K. The inner end of each lever terminates in a gear segment 40' and is normally rocked downwardly against a locating shoulder 40" on the casing by a torsion spring 42 wound about a pin 41. An escapement lever pivoted on a shaft 44 supported by the wall 24 and the partition 25 has a gear segment 44' meshing with the segment 40'. The escapement lever has a camming pawl 46 engageable with a pawl plate 47 forming a driving member associated with the numeral wheel of lowest order. The pawl plate 47 is ratchet connected to the count wheel of lowest order so that the wheels may be reset without imparting rotation to the pawl plate. 40 The ratchet connection may be the same as shown in the previously noted Slye Patent No. 2,004,881. The pawl plate has peripherally spaced, laterally extending lugs 47' and interposed grooves 47" arranged to receive the pawl 46 during each cycle of movement of the escapement lever 43 whereby a rotary indexing movement is imparted to the count wheel of lowest order. The driving connection between the key lever and the counter wheel of lowest order is a well-known one and need not further be described except that it may be noted that upon each operation of the key lever the wheel of lowest order is indexed in two steps, and when the key lever is in its normal position, the pawl plate and cam cooperate to hold the counter wheel of lowest order against accidental rotation. It will be observed from Figs. 3 and 4 that when the key lever is in its normal position, the camming pawl 46 is positioned between adjacent lugs 47'. It is, of course, understood that each counter unit may be provided with any suitable number of counter wheels, and the transfer mechanism between the adjacent wheels may be of any suitable sort.

70 The totalizer unit is operated in the same general manner as are the individual counter units.

but in the case of the totalizer a return lever 40a is used instead of the key lever 40. This return lever 40a is operated in the manner later described. As the connecting parts between the lever 40a and the wheel of lowest order of the totalizer are the same as the connection between the key lever and the first counter wheel of each individual counter unit, like numerals are employed to designate similar parts in the drawings.

When the assembly includes a totalizer unit T, there is provided a drive arrangement between the several individual or sub-counter units and the totalizer unit of such character that each actuation of each individual unit is transferred to the count wheels of the totalizer unit without affecting the other individual units. In this present instance, this drive arrangement includes a drive shaft 50 extending through each of the counter units C and through the totalizer and journaled in their respective end walls. Pawls 50' are respectively keyed to shaft 50 adjacent each of the levers 43 associated with the sub-counter units, and projecting fingers 50" on these pawls are located beneath laterally projecting studs 43' on levers 43 so that an individual downward movement of any of the levers 43 in response to a depression of a corresponding key lever 40 results in a partial counter-clockwise rotation of shaft 50, as viewed in Fig. 3. A pawl 51 which may be a duplicate of pawl 50' is mounted on shaft 50 in the totalizer and in reversed relation to pawls 50' so that a finger 51' associated therewith overlies a stud 43" laterally projecting from lever 43 of the totalizer. The fingers 50" and 51' are so located that they normally contact with their respective studs 43' and 43". Hence, a depression of any one of the keys results in a corresponding movement of the pawl 46 associated with said key and the pawl 46 of the totalizer, thus simultaneously operating the counter wheels of lowest order in the counter unit being operated and in the totalizer. It will thus be seen that each time any one of the individual units is operated to add a count, the totalizer is simultaneously operated to add a count, and, therefore, the totalizer will indicate the grand total of all the counts entered in all of the sub-counter units. The spring 42 in the totalizer acts through return lever 40a to shift totalizer lever 43 to its initial position of Fig. 4 so that stud 43" acts on finger 51' to return shaft 50 and pawls 50' to their starting positions after a key K is released.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. In a counting mechanism, a plurality of similar separable counter units arranged in side by side relation; means for securing said counter units in said relation, each unit including a casing, a reset shaft journaled therein, and counter wheels supported by said reset shaft; a reset

- operating shaft aligned with said reset shafts and located at one end of the line of units, detachable driving connections between the adjacent ends of adjacent shafts, and spring means urging said shafts longitudinally into tight driving relation with one another whereby lost motion is avoided when the reset shafts are turned by said operating shaft.
2. In a counting mechanism, a plurality of similar separable counter units arranged in side by side relation; means for securing said counter units in said relation, each unit including a casing, a reset shaft journaled in the casing, and counter wheels supported by said shaft; the adjacent ends of adjacent shafts respectively having a tapered groove and a tapered tongue fitting in the groove whereby adjacent shafts are connected in driving relation to one another, a reset operating shaft aligned with said reset shafts and having a like tongue and groove connection with the reset shaft adjacent thereto, and spring means normally urging said shafts longitudinally towards one another to prevent lost motion between the several shafts.
3. In a counting mechanism, a plurality of similar separable counter units arranged in side by side relation; means for securing said counter units in said relation, each unit having a casing, a reset shaft journaled in the casing for slight longitudinal floating movement, and counter wheels supported by said shaft; said shafts being aligned when said units are assembled and having tapered tongue and groove driving connections at their adjacent ends, a reset operating shaft having a tongue and groove driving connection with the reset shaft of the first unit, and spring means for urging said shafts longitudinally towards one another so as to prevent lost motion in the driving connections.
4. In a counting mechanism, a pair of spaced brackets, tie rods secured at their ends to said brackets, a plurality of counter units mounted in aligned side by side relation on said rods and clamped between the brackets, correspondingly located reset shafts in said counter units, each of said shafts having at its opposite ends tongue and grooved portions adapted to be received in mating driving relation with a corresponding portion of an adjacent shaft, a spring pressed member in one of said brackets engageable with the end of a reset shaft, and a spring pressed manually operable member journaled in the other bracket and engaged in driving relation with another of said reset shafts.
5. In a counting mechanism, a pair of spaced brackets, a plurality of counter units mounted in side by side relation between said brackets, each of said counter units including a reset shaft, connections on said shafts for interengaging an adjacent shaft in driving relation when said units are assembled, a reset operating shaft carried by one of said brackets and having interengaging driving relation with the reset shaft of the unit adjacent thereto when the units are assembled, and means rigidly connecting said brackets together and aligning said reset shafts and said reset operating shaft in cooperative engagement.

EDWARD WILD. 35
